VARIABLE FLOW PUMP

Cecil L. Moore, Indianapolis, Ind., assignor to Engineering & Research Lab. Service Co., Indianapolis, Ind., a company of Indiana

Filed May 31, 1957, Ser. No. 662,781

5 Claims. (Cl. 103—120)

This invention relates generally to displacement type pumps, and particularly to a pump of this type which can deliver a variable volumetric flow at constant pressure.

In the pumping of hydraulic fluids to supply fluid under pressure to hydraulic motors or other hydraulic components, it is advantageous to provide for varying the volumetric flow of the fluid without varying the pressure of the fluid supplied to the hydraulic component. The preferred embodiment of the present invention provides a gear pump in which the gears may be variably displaced, relative to each other, to thereby vary the zone of mesh of the gear teeth. As the gears are relatively positioned, the space between the unmeshed teeth of the gears is simultaneously plugged or filled by means of members having appropriately shaped fingers extending therefrom.

In the preferred embodiment of the invention, the relative positioning of the gears and the plugging of the space between the unmeshed gear teeth is accomplished in response to variations in the pump outlet pressure. Because the zone of mesh of the gears (and consequently the volumetric delivery of the pump) is varied inversely with the pump outlet pressure, the pump tends to hold a constant outlet pressure under varying demands. This characteristic of the pump makes it particularly useful in supplying fluid pressure to a variable speed hydraulic motor which operates at constant pressure.

A further object of the present invention is to provide a variable delivery pump having a volumetric delivery relatively independent of the speed of rotation of the pump driving means.

A further object is to provide a pump which can deliver fluid at a constant pressure under variable demand, the delivery of the pump being independent of the rotational speed of the pump driving means.

A further object is to provide a pump having a volumetric delivery which is variable in response to a control pressure.

The full nature of the invention will be understood from the accompanying drawings and the following description and claims:

Fig. 1 is a perspective view of the apparatus embodying the present invention, with portions broken away to illustrate the internal arrangement.

Fig. 2 is a side sectional view of the apparatus shown in Fig. 1.

Fig. 3 is a view similar to Fig. 2 but illustrating the parts in different relative position.

Referring to the drawings, an elongated housing 10 has end plates 11 secured thereto by means of bolts 12. A drive shaft 13 extends through the housing and is journaled in bearings 14 which are fixed in the end plates by means of pins 16. Splined to the shaft 13 is a drive gear 17 having teeth 18 thereon. As may best be seen in Fig. 1, the gear 17 has appreciable length along its axis of rotation.

2

As shown in Fig. 2, the internal surface of the axial opening through the gear 17 is splined at 19, this splined area cooperating with an appropriately splined area 21 on the shaft 13 to permit rotation of the gear by the drive shaft.

A tubular stationary member 22 extends through the lower portion of the housing parallel to the drive shaft. Member 22 is supported by the end plates and is locked therein by means of a pin 23. An idler gear 24 is journaled for rotation on the tubular member by means of bushings 26. The idler gear carries teeth 27 thereon adapted to mesh with the teeth of the driving gear. From the foregoing it will be understood that the drive gear is rotated by the drive shaft 13, but is capable of being axially displaced on the shaft because of its splined connection thereto, and that the idler gear is free to rotate about the tubular member 22, but can be axially displaced along the tubular member.

The means for axially displacing the gears, thereby varying the zone of mesh therebetween, comprises a ram, or piston 28 having a central opening therethrough accommodating the drive shaft. The outer end of the piston terminates short of the housing end plate to provide a cavity or pressure chamber 29 for the purpose of which will be subsequently explained. Beneath and adjacent the piston 28 is a member 31 journaled for rotation on the tubular member 22 and having multiple extending fingers 32. As may best be seen in Fig. 1, the fingers are appropriately shaped so that they fit snugly within the space between the teeth of the idler gear 24. An axial cavity within the member 31 accommodates a compression spring 33 which extends between a shoulder formed at the outer end of the member 31 and a washer 34 which in turn bears against the idler gear. The non-rotating piston 28 and the rotating member 31 are joined for unitary movement along the drive shaft and tubular member by means of a ring-shaped key 36 which extends into a keyway or annular groove formed in the member 31 and a cooperating retainer ring 37 threaded upon the reduced outer end of the member. The piston 28 and the member 31 are thus adapted to move in unison within the housing, the limit of their leftward movement (as viewed in Fig. 2) being established by the stop or spacer 38.

At the opposite end of the housing there is accommodated on the tubular member a piston 39, similar to the piston 28, and a pressure chamber 41, similar to chamber 29, is provided at its outer end. Adjacent to and above the piston 39 is a rotatable member 42 journaled on the drive shaft and similar to the member 31. Member 42 carries extending fingers 43 adapted to fit snugly within the space between the teeth 18 of the drive gear. A compression spring 44, similar to spring 33, extends between the end of the member 42 and the gear 17. A retainer ring 46 threaded on the end of member 42 provides a keyway for an annular key 48 which serves to permit the piston 39 and the member 42 to be moved axially in unison, but allows member 42 to be rotated upon the drive shaft while piston 39 is non-rotatably mounted on the tubular member 22.

The pump assembly above described has opposed fluid inlet and outlet openings through the housing, only the outlet opening 49 being shown. A fluid passage 51 has communication with the outlet opening and at 52 and 53 with the chambers 29 and 41, respectively.

In operation, with the drive shaft rotating at a given speed, and with the zone of mesh of the gear teeth extending as indicated in Fig. 2, fluid will be drawn into a fluid receiving chamber bounded by the adjacent teeth of the gears, and, as the gears mesh, the fluid will be displaced from the chamber and delivered through the out-

let opening. By means of the passage 51 the fluid pressure at outlet 49 will also exist within the chambers 29 and 41. Should this outlet pressure increase because of, for example, decreased demand, the pressure within the chambers 29 and 41 will be correspondingly increased. The increased pressure within these chambers will displace the piston 28 rightwardly and the piston 39 leftwardly, as viewed in Fig. 3. This movement of the pistons from their position of Fig. 2 to their position of Fig. 3, will be opposed by the force exerted by springs 33 and 44.

As will be apparent from Fig. 3, this displacement of the pistons correspondingly displaces the gear 17 and 24 relative to each other and decreases the zone of the mesh of their teeth. As the gears are displaced by their abutting pistons, it will be apparent that the adjacent fingers on the members 42 and 31, rotating with the gears, will be inserted into the spaces between the gear teeth. This shortening of the zone of mesh of the gear teeth and the corresponding plugging or occupation of the space between the unmched teeth of each of the gears thus serves to reduce the volumetric output of the pump and thereby returns the pressure of the fluid delivered by the pump back to a value approaching its original magnitude.

Upon a decrease in outlet pressure caused by, for example, an increase in demand, the pressure within the chambers 29 and 41 will correspondingly decrease. Springs 33 and 44 will thereupon move outwardly members 31 and 42, together with pistons 28 and 39, thereby increasing the zone of mesh of the gear teeth. The volumetric delivery of the pump will thereupon be increased to bring the fluid pressure delivered by the pump back to a value approaching its original magnitude.

It will be understood that these compensating movements of the gears take place relatively rapidly so that their regulating effect on the pump outlet pressure occurs almost instantaneously. It should be further evident that the relative position of the gears shown in Fig. 2 represents an intermediate position and that the position of the gears shown in Fig. 3 represents a near-limiting position, the compressed lengths of the springs 33 and 44 being such as to prohibit complete unmaching of the gears. At the other limit of relative motion of the gears the stops 38 also prohibit complete unmaching of the gears.

It will be apparent that the compensating action on the fluid pressure caused by relative movement of the gears would also occur if the variation in pressure occurred, not because of an increase in demand, but because of the variation in speed of the drive shaft. Thus, the pump can provide a constant outlet pressure although the speed of rotation of the drive shaft should vary.

Although the preferred embodiment herein disclosed illustrates the pressures in chambers 29 and 41 to be a function of the pump outlet pressure, it will be apparent that passage 51 could be omitted and the pressure within the chambers could be made a function of an external controlling pressure which is independent of the fluid being pumped. Control of the volumetric delivery of the pump can thus be accomplished independently of the pressure of the fluid being pumped.

While the invention has been disclosed and described in some detail in the drawings and foregoing description, they are to be considered as illustrative and not restrictive in character, as other modifications may readily suggest themselves to persons skilled in this art and within the broad scope of the invention, reference being had to the appended claims.

The invention claimed is:

1. A constant pressure variable flow pump of the gear type comprising an elongated housing and a drive shaft extending therefrom, a drive gear splined to the drive shaft within said housing, a meshing idler gear rotatably mounted within said housing and adapted to be displaced longitudinally therein, opposed inlet and outlet

openings in the housing adjacent the zone of mesh of said gears, and means responsive to pump outlet pressure for simultaneously varying the magnitude of the zone of mesh of said gears and for plugging the area between the unmched teeth of said gears, said means comprising dual pistons movable in opposite directions upon a variation in pump pressure, members axially aligned with each of said gears and movable with said pistons, multiple extending fingers on each of said members positioned within the area between the unmched teeth of said gears upon movement of said pistons, and resilient means disposed centrally of and extending axially with the fingers of each of said members for urging said fingers out of the area between the unmched teeth of said gears, whereby the pump outlet pressure is balanced against the force exerted by said resilient means to modulate the volumetric delivery of the pump.

2. A constant pressure variable flow pump of the gear type comprising an elongated housing and a rotatable drive shaft extending therefrom, a drive gear splined to the drive shaft within said housing, a meshing idler gear rotatably mounted within said housing and adapted to be displaced longitudinally therein, opposed inlet and outlet openings in the housing adjacent the zone of mesh of said gears, and means responsive to a control pressure for simultaneously varying the magnitude of the zone of mesh of said gears and for plugging the area between the unmched teeth of said gears, said means comprising dual pistons each contiguous with one of said gears and movable in opposite directions in response to changes in said control pressure, members axially aligned with each of said gears and movable with said pistons, multiple extending fingers on each of said members positioned within the area between the unmched teeth of said gears upon movement of said pistons, and resilient means disposed centrally of and extending axially with the fingers of each of said members for urging said fingers out of the area between the unmched teeth of said gears, whereby said control pressure is balanced against the force exerted by said resilient means to modulate the volumetric delivery of the pump.

3. A constant pressure variable flow pump of the gear type comprising an elongated housing and a drive shaft extending therefrom, a drive gear splined to the drive shaft within said housing, a meshing idler gear rotatably mounted within said housing and adapted to be displaced longitudinally therein, opposed inlet and outlet openings in the housing adjacent the zone of mesh of said gears, means responsive to pump outlet pressure for simultaneously varying the magnitude of the zone of mesh of said gears and for plugging the area between the unmched teeth of said gears, said means comprising dual pistons movable in opposite directions upon a variation in pump outlet pressure, members axially aligned with each of said gears and movable with said pistons, multiple extending fingers on each of said members positioned within the area between the unmched teeth of said gears upon movement of said pistons, and resilient means disposed centrally of and extending axially with the fingers of each of said members for biasing said gears into a relative position wherein their zone of mesh is a maximum, whereby the pump outlet pressure is balanced against the force exerted by said resilient means to modulate the volumetric delivery of the pump.

4. A constant pressure variable flow pump comprising a housing and a drive shaft extending therefrom, a drive gear splined to the drive shaft within said housing, a meshing idler gear relatively mounted within said housing upon an axis parallel to said drive shaft and adapted to be displaced along said axis, opposed inlet and outlet openings in the housing adjacent the zone of mesh of said gears, means responsive to pump outlet pressure for simultaneously varying the magnitude of the zone of mesh of said gears and for plugging the area between the unmched teeth of said gears, said means comprising

dual pistons movable in opposite directions upon a variation in pump outlet pressure, a member movable with each of said pistons having multiple extending fingers, the fingers on each of said members being positioned within the area between the unmeshed teeth of said gears upon movement of said pistons, and resilient means disposed centrally of and extending axially with the fingers of each of said members for urging said fingers out of the area between the unmeshed teeth of said gears, whereby the pump outlet pressure is balanced against the force exerted by said resilient means to modulate the volumetric delivery of the pump.

5. A constant pressure variable flow pump comprising a housing and a drive shaft extending therefrom, a drive gear splined to the drive shaft within said housing, a meshing idler gear rotatably mounted within said housing upon an axis parallel to said drive shaft and adapted to be displaced longitudinally along said axis, opposed inlet and outlet openings in the housing adjacent the zone of mesh of said gears, and means responsive to pump outlet pressure for simultaneously varying the magnitude of the zone of mesh of said gears and for plugging the area between the unmeshed teeth of said gears, said means in-

cluding a piston movable upon a variation in pump outlet pressure for displacing one of said gears, a member movable with said piston having multiple extending fingers, the fingers on said member being positioned within the area between the unmeshed teeth of the other of said gears upon movement of said piston, and resilient means disposed centrally of and extending axially with the fingers of each of said members for urging said fingers out of the area between the unmeshed teeth of said gears, whereby the pump outlet pressure is balanced against the force exerted by said resilient means to modulate the volumetric delivery of the pump.
